UNITED STATES PATENT OFFICE.

JOHANN STUMPF, OF BERLIN, GERMANY, ASSIGNOR TO GENERAL ELECTRIC COMPANY, A CORPORATION OF NEW YORK.

TURBINE.

No. 822,315.

Specification of Letters Patent.

Patented June 5, 1906.

Application filed November 4, 1901. Serial No. 81 121.

To all whom it may concern:

Be it known that I, JOHANN STUMPF, a subject of the King of Prussia, German Emperor, and a resident of 27 Rankestrasse, Berlin, in the Kingdom of Prussia, German Empire, have invented certain new and useful Improvements in Turbines, of which the following is an exact specification.

Turbine-wheels have been heretofore constructed in which single U-shaped buckets are employed; but such an arrangement is open to serious objections. Chief among these may be mentioned the tendency to end thrust, improper action of the buckets resulting from an expansion or contraction of the fluid jet or column after it leaves the admission-nozzle, due to a difference in pressure between the jet and the fluid medium within the casing, and the improper action of the buckets, due to the lack of proper alinement with the nozzle. If the pressure within the turbine-casing is less than that of the steam-jet, the latter in leaving the admission-nozzle expands before entering the bucket, so that part of the steam-jet will flow upon the surface of the wheel without entering the buckets and performing useful work. In case the pressure within the casing is above that of the steam-jet the latter contracts, so that it does not flow exactly along the side wall of the buckets, but strikes the curved portion thereof at a point some distance from the wall, thereby causing shocks or disturbances in the turbine. Furthermore, turbines fitted with such buckets are open to the disadvantages arising from the lateral movement of the turbine-wheel. Turbine-wheels have also been constructed of the so-called "Pelton" type. The buckets of these wheels consist of two ball-shaped or ellipsoidal buckets which meet in the middle of the turbine-wheel. These Pelton buckets have, however, the great disadvantage that they do not correctly guide the steam-jets entering the same and also that a stowing and whirling of the steam takes place in the buckets, in consequence whereof the velocity of the steam cannot be fully transferred into useful work.

The object of my present invention is to overcome these disadvantages.

In order to make my invention more clear, I refer to the accompanying drawings, in which similar letters denote similar parts

throughout the several figures, and in which—

Figure 1 is a plan view of a part of the circumference of a turbine-bucket wheel. Fig. 2 is a sectional view taken on line *x* *x* of Fig. 1 and showing the annular nozzle located adjacent thereto, and Fig. 3 is a section on line *y* *y* of Fig. 2.

In the drawings, *b* is the admission-nozzle, comprising a plurality of closely-associated passages discharging steam or other elastic fluid in the form of a solid stream or jet. The partitions between the nozzle-passages extend in the same general direction as the thin partitions between adjacent pairs of buckets.

d d are the single buckets, forming a double bucket.

e is the wedge-shaped partition, situated between the two buckets *d d*, the latter being located side by side, and *k* is a thin sharp-ended partition situated between and forming a wall of the buckets *d d*. It is to be noted that each partition *k* extends substantially tangential to the periphery of the wheel and that the partitions extend substantially parallel and form the top and bottom walls of the bucket-spaces. In the buckets *d* the column of steam is split into two parts at the partition *e*, and each part is reversed, after which the steam leaves the turbine-wheel substantially in the manner shown in Fig. 3 of the drawings. The steam leaving the wheel-buckets strikes surfaces, such as the curved surfaces forming the sides of the nozzles, and is deflected outward thereby away from the wheel to prevent it from reacting thereon. By reason of the fact that the lower and upper walls of each bucket *d* are perfectly flat and also that the walls are about parallel to one another the steam leaves these buckets in nearly parallel layers, so that each steam-jet is guided between the foregoing and the following steam-jet.

By reason of the construction described the disadvantages due to steam-whirls are prevented.

Owing to the arrangement of the buckets, the action of the jet is independent of the pressure in the casing, which pressure may vary widely under varying load conditions. The expansion or contraction of the jet or column does not affect their action, because the partition *e* is directly in line with a plane pass-

ing through the nozzle. The partition being central divides the column of steam or other fluid equally and prevents end thrust. An axial movement of the wheel does not seriously interfere with the operation, because all of the steam will continue to enter the buckets. Any slight decrease in the amount of steam entering one side of the partition is compensated for by a corresponding increase on the other side.

The buckets *a* being situated one partly above the other, with only a thin partition *k* between them, the steam leaving the nozzle-passages freely enters the same and the entire energy contained in the steam is thus converted into work under the most favorable conditions.

I have referred to steam as the motive fluid; but the invention is not necessarily limited thereto, since other kinds of fluid can be employed.

In accordance with the provisions of the patent statutes I have described the principle of operation of my invention, together with the apparatus which I now believe to represent the best embodiment thereof; but I desire to have it understood that the apparatus shown is only illustrative and that the invention can be carried out by other means.

What I claim as new, and desire to secure by Letters Patent of the United States, is—

1. In an elastic-fluid turbine, the combination of a support, a plurality of double buckets carried by the support, each double bucket having a wedge-like partition situated between the buckets, and thin flat partitions situated between the adjacent double buckets, which assist in confining and directing the passage of motive fluid as it passes into and out of the bucket-spaces.

2. In an elastic-fluid turbine, the combination of a rotary support or wheel, a plurality of double undercut buckets formed in the rim

thereof, each bucket-space occupying a plane substantially tangential to a radius, wedge-like partitions between each two buckets which divide the fluid stream, and thin flat partitions which extend substantially parallel and form the top and bottom walls of the bucket-spaces.

3. In an elastic-fluid turbine, the combination of a wheel having double buckets, each double bucket having a wedge-like partition for dividing the fluid stream and thin flat partitions which form the top and bottom walls of adjacent buckets, a nozzle which surrounds the wheel to a greater or less extent and comprises a plurality of closely-associated passages which discharge motive fluid against the wedge-like partitions.

4. In an elastic-fluid turbine, the combination of a wheel having buckets with spaces between them occupying planes substantially tangential to the periphery of the wheel, a nozzle which presents its discharge-orifices to the buckets, and means for deflecting the exhaust fluid away from the wheel.

5. In an elastic-fluid turbine, the combination of a wheel having double buckets on its periphery, each double bucket having a wedge-like partition for dividing the stream of motive fluid, partitions which form the top and bottom walls of the buckets, a nozzle surrounding the wheel to a greater or less extent and comprising a plurality of closely-associated discharge-passages, the axes of the passages coinciding with a plane passing through the wedge-like partitions.

In testimony whereof I have signed my name to this specification in the presence of two subscribing witnesses.

JOHANN STUMPF.
